UNITED STATES PATENT OFFICE.

ISRAEL SCRANTON, OF DECATUR, ILLINOIS.

LUBRICATING DEVICE.

Application filed July 5, 1918. Serial No. 243,268.

To all whom it may concern:

Be it known that I, ISRAEL SCRANTON, a citizen of the United States, residing at Decatur, in the county of Macon and State of Illinois, have invented certain new and useful Improvements in Lubricating Devices, of which the following is a specification.

My invention relates to improvements in lubricating devices and particularly for lubricating axles, driving boxes and the like.

One of the objects of my invention is the provision of such a device and construction which gives most efficient results in practical operation, which is simple in construction and readily installed and removed and which thoroughly lubricates and reduces the lateral wear to a minimum.

Further objects of this invention will appear from a consideration of the following specification.

To the accomplishment of the foregoing and such other objects as may hereinafter appear, my invention consists in the construction, combination and arrangement of parts hereinafter described and then sought to be defined in the appended claims, reference being had to the accompanying drawings forming a part hereof and which shows merely for the purpose of illustrative disclosure one embodiment of my invention, it being expressly understood, however, that various changes may be made in practice within the scope of the claims without digressing from my inventive idea.

In the drawings,

Fig. 1 represents a longitudinal section through a driving box constructed and equipped with devices embodying my invention.

Fig. 2 is a sectional and elevational view taken substantially on line 2-2 of Fig. 1 and looking in the direction of the arrow.

Fig. 3 is a vertical transverse sectional view taken substantially on line 3-3 of Fig. 1, and looking in the direction of the arrow.

Fig. 4 is a detailed section indicating the means for fastening the springs in position.

In the drawings the numeral 1 designates an axle to which the wheel 2 is secured, this wheel being provided with a brass hub plate 3, as in the case of locomotive driving wheels and the like. The box 4 is supported on the axle and is of customary construction with the exceptions hereinafter pointed out, and

55 has the flat hub face 5 and the usual driv-

ing brass 6. The lower part of this box is provided with straight faces or guides 7 to receive a lubricating cellar and to form the legs or lugs 8 which are spaced apart, as shown, and provided with the apertures 9 therethrough.

The cellar as a whole is designated by the reference character 10 and includes the straight side members 11, the rear end member 12 and a front end member 13, as well as the top member 14 which is of concave shape to fit the axle, as is well understood. This top member 14 is formed with a plurality of perforations or of reticulate material in order to permit the passage of the lubricant therethrough, as is well understood. Mounted for movement within the receptacle formed by the side members 11, the end members 12 and 13 and the top member 14 is the follower plate 15, around the edges of which I provide the gasket 16 for tight engagement with the sides and ends of this receptacle.

This device is adapted for use with either a hard lubricant or what is called a soft lubricant, such as soft grease or hard oil, and in the event of the use of the latter, I interpose a layer of felt 17 underneath the top member 14, so as to restrict the supply of lubricant to the axle and hub. It is also to be noted that in the hub end plate 13, I provide a series of apertures or openings 18 for the purpose of supplying a suitable supply of lubricant directly to the inner face of the hub plate and thereby prevent lateral wear by providing proper lubrication at this point, but it is to be expressly understood that I may provide any number of these holes or apertures instead of the single series or row, as shown.

In order to provide a sustained pressure against the follower plate 15 sufficient to cause the proper feed of the lubricant through the top member 14 and the hub end member 13, I support the coil spring 19 on the plate member 20 which extends transversely across the lower part of the cellar from one side member 11 to the other, this plate member 20 being slightly dished so as to receive the lower end of the spring 19, which is preferably of inclined or conical shape. This spring 19 is merely for the purpose of feeding the lubricant to the axle and hub.

For the purpose of holding the cellar as

a whole, in proper position, I provide the stronger spring 21, which is of double conical shape and the upper end of which embraces the projection in the plate 20 formed by dishing the same. The lower end of this spring 21 is supported in the suitable supporting plate 22. This plate 22 is itself supported from suitable spreader jacks, hereinafter described, which are interposed 5 between the spaced legs or lugs 8 of the box construction to prevent the box from closing or for opening the box if it closes when the cellar is removed. Each spreader jack comprises a body member 24 having the reduced 10 screw threaded portion 25 which receives the internally threaded sleeve part 26, the ends of each of these elements being provided with shoulders for engagement with the inner faces of the legs or lug 8 and the 15 outer surface of which is formed of a polygonal shape for the application of a suitable tool. Each spreader jack as a whole, is provided with an aperture therethrough to permit the passage of the securing pin or 20 bolt 27, one end of which is downturned, as at 28, and the other end of which receives the cotter pin or other suitable fastening 25. Plate 22 has its ends turned or looped 29. Plate 22 has its ends turned or looped around each spreader jack whereby it is 30 properly supported in position.

It is to be noted that the follower plate 15 is provided with apertures to receive the usual filler tubes 30 and also that the springs 35 may be secured to their various plates by any suitable means, the clip 31 shown in detail in Fig. 4, being one construction for that purpose.

This construction, therefore, is seen to be a very simple one for accomplishing the 40 efficient lubrication, not only of the axle, but also of the bearing plate of the hub of the wheel, thereby reducing the lateral wear so that the brasses or other bearings have to be renewed only after a considerable and 45 large amount of travel. It is also to be noted that the lower spring 21 in addition to holding the cellar up to its normal operating position against the axle also tends to force the cellar toward the hub of the 50 wheel so that in the case of lateral movement of the wheel the spring will always cause a sort of tilting or sidewise movement of the cellar so that the hub face thereof will always be in engagement with the hub plate 55 and thereby efficiently lubricate the same and reduce the wear thereof.

It is also in order to reduce the wear of 60 this brass hub plate and the other parts that I provide the dust ring construction. This comprises the substantially circular bearing ring 32 provided at intervals with suitable socket members 33 to receive the springs 34, the construction as a whole fitting in a suitable groove or recess 35 formed in the outer 65 or hub face of the box 4. This groove or re-

cess is of such depth that the ring 33 may be forced therein flush with the outer face of the box 4. It is to be noted that the ring is not in the form of a complete circle, the ends terminating short of each other a distance apart equal to the width of the cellar. It is for the purpose of closing the lower part of the opening between the cellar and the hub that I extend the hub end plate 13 of the cellar, as heretofore described, and 70 as shown in Figs. 1 and 2, so that there is a tight engagement entirely around the brass hub plate 3 at all times to prevent the ingress of dirt, dust and other material which would increase the wear and tear on these 80 parts.

Having described my invention, what I claim is:

1. In a device of the character described, and in combination with an axle box, an 85 axle passing therethrough and a wheel on one end of said axle with its hub bearing against said axle box, a lubricant cellar movably mounted between the legs of the axle box and arranged to apply lubricant 90 to the axle and to the hub and means for holding the cellar as a whole in position against the axle and against the hub.

2. In a device of the character described and in combination with an axle box, an 95 axle passing therethrough, and a wheel on one end of said axle with its hub bearing against said axle box, a lubricant cellar movably mounted between the legs of the axle box, said cellar having an open bottom 100 and a follower plate therein and arranged to apply lubricant to the axle and to the hub, and means for holding the cellar as a whole in position against the axle and against the hub.

3. In a device of the character described and in combination with an axle box, an axle passing therethrough, and a wheel on one end of said axle with its hub bearing against said axle box, a lubricant 110 cellar movably mounted between the legs of the axle box, said cellar having openings in its top member and also in its hub end for applying lubricant to the axle and to the hub, and means for holding the cellar as a 115 whole in position with the top member against the axle and with the hub end against the hub.

4. In a device of the character described and in combination with an axle box, an 120 axle passing therethrough, and a wheel on one end of said axle with its hub bearing against said axle box, a lubricant cellar movably mounted between the legs of the axle box, said cellar having an open bottom and a follower plate therein and also having openings in its top member to permit the application of lubricant to the axle and openings in its hub end member to permit the application of lubricant to the hub, a support- 125 130

- ing member extending across the bottom of the cellar and a spring supported thereby and engaging said follower plate for forcing the lubricant out of the cellar and means 5 for holding the cellar as a whole in position with the top member against the axle and with its hub member against the hub.
5. In a device of the character described and in combination with an axle box, an 10 axle passing therethrough, and a wheel on one end of said axle with its hub bearing against said axle box, a lubricant cellar movably mounted between the legs of the axle box, said cellar having an open bottom 15 and a follower plate therein and also having openings in its top member to permit the application of lubricant to the axle and openings in its hub end member to permit the application of lubricant to the hub, a 20 supporting member extending across the bottom of the cellar and a spring supported thereby and engaging said follower plate for forcing the lubricant out of the cellar and an additional supporting element located below the bottom of the cellar, and a 25 spring resting on said additional supporting element and engaging said first mentioned support for holding the cellar in position with the top member against the axle 30 and with the hub member against the hub.
6. In a device of the character described and in combination with an axle box, an axle passing therethrough, and a wheel on one end of said axle with its hub bearing against 35 said axle box, a lubricant cellar movably mounted between the legs of the axle box, said cellar having an open bottom and a follower plate therein and also having openings in its top member to permit the application 40 of lubricant to the axle and openings in its hub end member to permit the application of lubricant to the hub, a supporting member extending across the bottom of the cellar and a spring supported thereby and engaging 45 said follower plate for forcing the lubricant out of the cellar and an additional supporting element located below the bottom of the cellar, and a spring resting on said additional supporting element and engaging 50 said first mentioned support for holding the cellar in position with the top member against the axle and with the hub member against the hub, said last mentioned spring being stronger and longer than the first mentioned spring so as to permit a tilting movement of the cellar as a whole relative to the 55 last mentioned support while maintaining the pressure of the spring tending to force the cellar against the hub.
- 60 7. In a device of the character described and in combination with an axle box, an axle passing therethrough, and a wheel on one end of said axle with its hub bearing against 65 said axle box, a lubricant cellar movably mounted between the legs of the axle box, spreading members detachably mounted between the legs of the axle box so as to hold them apart, a supporting member connected to said spreading member and a spring resting on said supporting member and engaging 70 said cellar for holding the same in position with the top member against the axle and with the hub end member against the hub.
8. In a device of the character described 75 and in combination with an axle box, an axle passing therethrough, and a wheel on one end of said axle with its hub bearing against said axle box, a lubricant cellar movably mounted between the legs of the axle 80 box, said cellar having an open bottom and a follower plate therein and arranged to apply lubricant to the axle and also to the hub, a supporting member connected to the lower end of the cellar, a spring supported 85 thereby arranged to exert pressure against the follower plate, spreader members detachably connected to the legs of the axle box for holding the same apart, another supporting member connected to said spreader 90 members and another spring mounted on said last mentioned supporting member and engaging said first mentioned support for holding said cellar in position with its top member against the axle and with its hub 95 end member against the hub.
9. In a device of the character described and in combination with an axle box, an axle passing therethrough, and a wheel on one end of said axle with its hub bearing 100 against said axle box, a lubricant cellar movably mounted between the legs of the axle box, said cellar having an open bottom and a follower plate therein and arranged to apply lubricant to the axle and also to the 105 hub, a supporting member connected to the lower end of the cellar, a spring supported thereby arranged to exert pressure against the follower plate, spreader members detachably connected to the legs of the axle box 110 for holding the same apart, another supporting member connected to said spreader members and another spring mounted on said last mentioned supporting member and engaging said first mentioned support for 115 holding said cellar in position with its top member against the axle and with its hub end member against the hub, each spreader member including a pair of shouldered members adjustable relative to each other, 120 the shoulders being adapted to engage the legs of the axle box and a bolt passing through said members and detachably mounted within the apertures in the legs of the axle box for holding the spreader members against unintentional detachment from their proper position.
10. In a device of the character described 125 and in combination with an axle box, an axle passing therethrough, and a wheel on 130

one end of said axle with its hub bearing against said axle box, a lubricant cellar movably mounted between the legs of the axle box, spreading members mounted between 5 the legs of the axle box so as to hold them apart, and means for holding the cellar in position so as to lubricate the axle.

11. In a device of the character described and in combination with an axle box, an 10 axle passing therethrough, and a wheel on one end of said axle with its hub bearing against said axle box, a lubricant cellar movably mounted between the legs of the axle box and arranged to apply lubricants to the 15 axle and to the hub, and a single spring for holding the cellar in position against the axle and against the hub.

12. In a device of the character described and in combination with an axle box, an 20 axle passing therethrough, and a wheel on one end of said axle with its hub bearing against said axle box, a lubricant cellar mounted for horizontal and vertical movement as a whole between the legs of the 25 axle box so as to apply lubricants to the axle and also to the hub and means for holding the cellar against the axle and also against the hub of the wheel.

13. In a device of the character described and in combination with an axle box, an 30 axle passing therethrough, and a wheel on one end of said axle with its hub bearing against said axle box, a lubricant cellar movably mounted between the legs of the axle 35 box and arranged to apply lubricant to the axle and to the hub, means for holding the cellar in position against the axle and against the hub, the upper plate of said cellar being perforated and a layer of felt 40 positioned in said cellar directly underneath said perforated plate to control the feed of the lubricant.

14. In a device of the character described and in combination with an axle box, an 45 axle passing therethrough and a wheel on one end of said axle with its hub bearing against said axle box, a lubricant cellar movably mounted between the legs of the axle 50 box and arranged to apply lubricant to the axle and to the hub, one end of said cellar bearing against the hub of the wheel and means for holding the cellar in position against the axle and against the hub, a dust 55 ring movably and resiliently mounted in the hub face of the axle box and bearing against the hub of the wheel so as to prevent the entrance of dust to the hub face of the wheel and box and also to the axle.

15. In a device of the character described and in combination with an axle box, an 60 axle passing therethrough and a wheel on one end of said axle with its hub bearing against said axle box, a lubricant cellar movably mounted between the legs of the axle 65 box and arranged to apply lubricant to the

axle and to the hub, one end of said cellar bearing against the hub of the wheel and means for holding the cellar in position against the axle and against the hub, the hub face of the axle box being provided with 70 a circular groove, a ring member fitting in said groove and resilient means for normally forcing said ring member out of said groove and against the hub of the wheel, so as to prevent the entrance of dust between the hub 75 face of the box and the hub of the wheel and the axle.

16. In a device of the character described and in combination with an axle box, an axle passing therethrough and a wheel on one 80 end of said axle with its hub bearing against said axle box, a lubricant cellar movably mounted between the legs of the axle box and arranged to apply lubricant to the axle and to the hub, one end of said cellar bearing against the hub of the wheel, and means for holding the cellar in position against the axle and against the hub, a dust ring 85 yieldingly mounted between the hub face of the axle box and the hub of the wheel so 90 as to prevent the entrance of dust to the hub face of the wheel and box and also to the axle.

17. In a device of the character described and in combination with an axle box, an 95 axle passing therethrough and a wheel on one end of said axle with its hub bearing against said axle box, a lubricant cellar movably mounted between the legs of the axle box and arranged to apply lubricant to the 100 axle and to the hub, one end of said cellar bearing against the hub of the wheel, and means for holding the cellar in position against the axle and against the hub, the hub end of the cellar being of sufficient 105 length to cover the lower portion of the brass hub plate, and a dust ring yieldingly mounted between the hub face of the axle box and the hub of the wheel, the lower ends of said ring terminating short of each 110 other, a distance apart equal to the width of the cellar.

18. In a device of the character described and in combination with an axle box, an 115 axle passing therethrough, and a wheel on one end of said axle with its hub bearing against said axle box, a lubricant cellar mounted for horizontal and vertical movement as a whole, between the legs of the 120 axle box so as to apply lubricants to the axle and also to the hub, and a member yieldingly and positively moving said cellar both horizontally and vertically at the same time.

19. In a device of the character described, and in combination with an axle box, an axle 125 passing therethrough and a wheel on one end of said axle with its hub bearing against said axle box, a lubricant cellar movably mounted between the legs of the axle box and arranged to apply a lubricant to the 130

axle and to the hub, and means confined beneath the cellar for holding the cellar as a whole in position against the axle and against the hub.

- 5 20. In a device of the character described and in combination with an axle box, an axle passing therethrough and a wheel on one end of said axle with its hub bearing against said axle box, a lubricant cellar 10 mounted for horizontal and vertical movement as a whole between the legs of the axle box so as to apply lubricants to the axle and also to the hub, and means confined beneath the cellar for moving the cellar both 15 horizontally and vertically at the same time.
21. In a device of the character described and in combination with an axle box, an axle passing therethrough and a wheel on one end of said axle with its hub bearing against 20 said axle box, a lubricant cellar mounted between the legs of the axle box, members mounted between and bearing against the legs of the axle box, said members being ad-

justable so as to force said legs of the axle box apart to release the cellar. 25

22. In a device of the character described and in combination with an axle box, an axle passing therethrough and a wheel on one end of said axle with its hub bearing against said axle box, a lubricant cellar 30 mounted between the legs of the axle box, adjustable means located between the legs of the axle box whereby they may be forced apart to release the cellar.

23. In a device of the character described 35 and in combination with an axle box, an axle passing therethrough and a wheel on one end of said axle with its hub bearing against said axle box, a lubricant cellar mounted between the legs of the axle box, a dust ring 40 mounted in the hub facing of the axle box and bearing against the hub of the wheel to prevent the entrance of dust.

In testimony whereof I hereunto subscribe my name.

ISRAEL SCRANTON.
